UNITED STATES PATENT OFFICE.

GEORGE W. FLOYD, OF SPOKANE, WASHINGTON.

DOUBLE-SHEAVE BLOCK.

1,077,268.

Specification of Letters Patent.

Patented Nov. 4, 1913.
Application filed March 1, 1913. Serial No. 751,624.

To all whom it may concern:

Be it known that I, GEORGE W. FLOYD, a citizen of the United States, residing at Spokane, in the county of Spokane and State of Washington, have invented a new and useful Double-Sheave Block, of which the following is a specification.

The present invention relates to a pulley or sheave block for falls, tackle or cables, and aims primarily to provide a block embodying a pair of sheaves or grooved pulleys journaled therein and having their peripheries arranged in close relation in order that the falls, tackle or cable may move between the two sheaves or pulleys.

It is also the object of the present invention to provide a device of the character indicated which shall be of novel and improved construction, the same being durable, substantial, simple, compact, and inexpensive, as well as efficient, serviceable and convenient in its use.

A further object of the present invention is to provide a double sheave block, between the sheaves of which the cable, falls or tackle may pass so as to be in operative engagement with one or the other or both of the sheaves at all times, the jumping of the cable from the sheaves and the binding of the cable being eliminated.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawings, wherein:

Figure 1 is a perspective view of the block. Fig. 2 is a central transverse section. Referring specifically to the drawing, the improved block embodies a strap 1 of suitable metal doubled to provide a pair of arms, the bight or bend 2 being reduced in order

that a shackle, hook or other member may be readily attached thereto, and the ends of the strap or arms thereof, being connected by the bolt 3. A pair of complementary sheaves or grooved pulleys 4 are journaled between the arms of the strap by means of the bolts 5, and their peripheries are in close relation. Lips 6 are struck or bent from the edges of the strap to engage the heads of the bolts to lock the bolts against turning.

The arms of the strap are straight and guards or strips 7 are attached to the arms of the strap between the sheaves, the said guards having intermediate outstruck offsets 8 fitting over the arms. The ends of the guards are disposed adjoining and tangential relative to the sheaves and extend to each side so as to retain the cable, falls or tackle in proper operative relation with the sheaves. The guards 7 also prevent the cables from binding. Rivets or securing members 9 are engaged through the arms of the strap and the offsets 8 to retain the guards in position.

The present block may be employed for divers purposes, it being noted that the cable in being passed between the sheaves may be properly guided thereby, the cable being continually in operative engagement with one or the other or both of the sheaves.

Having thus described the invention, what is claimed as new is:

In a device of the character described, a double strap, a pair of sheaves journaled between the arms thereof, and having their peripheries in close relation, and laterally disposed guards secured to the arms of the strap intermediate the sheaves with their ends arranged adjoining and tangential to the sheaves.

In testimony that I claim the foregoing as my own, I have hereto affixed my signature in the presence of two witnesses.

GEORGE W. FLOYD.
